CLAIM

The ornamental design for display screen or portion thereof with animated user interface, as shown and described.

DESCRIPTION

FIG. 1 is the first image in a sequence of a display screen or portion thereof with animated user interface showing our new design.

FIG. 2 is the second image thereof.

FIG. 3 is the third image thereof; and,

FIG. 4 is the fourth image thereof.

The appearance of the animated user interface sequentially transitions between the images shown in FIGS. 1-4.

The process or period in which one image transitions to another forms no part of the claimed design. The broken lines are for the purpose of illustrating environmental structure and forms no part of the claimed design.
